UNITED STATES PATENT OFFICE.

ANTHONY V. HOLEC, OF NEW YORK, N. Y.

NAIL-POLISHING MACHINE.

1,207,755.

Specification of Letters Patent. Patented Dec. 12, 1916.

Application filed March 26, 1915. Serial No. 17,169.

To all whom it may concern:

Be it known that I, ANTHONY V. HOLEC, a subject of the Emperor of Austria-Hungary, residing at New York, in the county of New York and State of New York, have invented certain new and useful Improvements in Nail-Polishing Machines; and I do hereby declare the following to be a full, clear, and exact description of the invention, such as will enable others skilled in the art to which it appertains to make and use the same.

The invention relates to a nail polishing machine.

The object of the present invention is to improve the construction of nail polishing machines and to provide a simple, practical and comparatively inexpensive nail polishing machine designed for use in manicuring parlors and elsewhere and capable of simultaneously cleaning and polishing the nails of both hands without injuring the same by the movement of the polishing surfaces longitudinally of the nails and in one direction with respect to the same so as to produce a perfect polish.

A further object of the invention is to provide a nail polishing machine of this character adapted to shape the nails as well as polish the same and capable of enabling cleaning and polishing material to be applied as desired during the operation of the machine.

The invention also has for its object to provide a nail polishing machine capable of polishing and cleaning the nails with great rapidity so that a small motor may be used without danger of heating the same by a relatively long continued use of the motor.

Another object of the invention is to provide a nail polishing machine equipped with lubricating means adapted to supply a lubricant to the bearings of the various parts of the machine without liability of permitting dust to enter the bearings.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawings, Figure 1 is a plan view of the nail polishing machine, the top and the lid or cover being removed, Fig. 2 is a similar view of the front portion of the machine, parts being omitted to show the lubricator clearly, Fig. 3 is a plan view illustrating the construction for operating the arms which carry the polishing and cleaning material to the rotary polishing element, Fig. 4 is a detail vertical sectional view on the line 4—4 of Fig. 1, Fig. 5 is a detail sectional view taken substantially on the line 5—5 of Fig. 4, Fig. 6 is a detail sectional view illustrating the arrangement of the means for operating the arm which supplies polishing material to the rotary self-polishing element and showing the means for normally holding the polishing material out of engagement with the rotary polishing element. Fig. 7 is a detail perspective view of one of the removable sections which carries the guide for spacing and guiding the nail polishing and cleaning material, Fig. 8 is a detail view illustrating the arrangement of the friction gearing for connecting the mechanism with the motor, Fig. 9 is a detail view of the rotary element for polishing the thumb nails. Fig. 10 is a side elevation of the nail polishing machine on a reduced scale, the cover being closed.

Like numerals of reference designate corresponding parts in all the figures of the drawings.

In the accompanying drawings in which is illustrated the preferred embodiment of the invention, 1 designates a casing designed to be constructed of hard wood or other suitable material and composed of a bottom 2, rear side walls 3 and front side walls 4 arranged substantially at right angles to each other and forming a tapered approximately triangular front portion as clearly illustrated in Fig. 1 of the drawings, but a casing of any other preferred configuration may of course be employed. The side walls 3 taper rearwardly and are connected by a rear wall 5 forming a truncated rearwardly tapered portion for the accommodation of a motor 6. The casing is provided with a rear top section or wall 7 and a hinged cover 8 which is hinged to the rear section or wall 7 of the top and which is adapted to be open to permit access to the nail polishing machine. The motor 6 which is a small electric motor is arranged in circuit with a switch 9 and with a cord 10 designed

to be provided with an ordinary plug, not shown for enabling the nail polishing machine to be connected with any suitable socket of an electric supply system but any 5 other suitable motor may of course be employed for operating the nail polishing mechanism, hereinafter described.

The shaft of the motor carries a beveled pinion 11 which meshes with a beveled gear 10 wheel 12 mounted for rotary movement on a fixed shaft or spindle 13 and connected with a friction gear 14 constructed of rubber or other suitable material and mounted on an annular flange 15 preferably formed 15 integral with the gear wheel 12. The friction wheel or pinion 14 is in frictional contact or engagement with a friction wheel 16 provided with a rib 17 of rubber or other suitable material. This provides a yield- 20 able drive between the motor and the nail polishing mechanism and will effectively prevent injury to the nails of the person being manicured.

The wheel 16 is mounted on a transverse 25 shaft 18 journaled in suitable bearings of spaced posts 19 and carrying beveled pinions 20 keyed or otherwise fixed to the ends of the shaft 18 and meshing with beveled gear wheels 21 of angularly disposed shafts 22 30 and 23 which carry the rotary horizontally disposed polishing elements 24. The shafts 22 and 23 are journaled in suitable bearings 25 and the shaft 22 is provided with an extension 26 having a beveled pinion 27 which 35 meshes with a beveled pinion 28 of a vertically disposed rotary polishing element 29 for cleaning and polishing the nails of the thumbs.

The rotary polishing element 29 is mounted 40 on a fixed vertical shaft 30 and rotates at the same speed as the horizontally disposed polishing elements 24 and in practice the rotary polishing elements which are in the form of rolls in the accompanying drawings 45 will rotate approximately five revolutions to the second but the gearing may be arranged in any suitable manner for rotating the cleaning and polishing rolls at any desired speed. Each of the horizontally disposed cleaning and polishing elements 24 50 consists of a roller constructed of wood or other suitable material and provided with four annular grooves 31 which present concaved surfaces that conform generally to the 55 configuration of the nails of the fingers. Each of the horizontally disposed cleaning and polishing rolls is provided with a soft flexible covering composed of two separate plies or covers 33 of chamois or other suitable 60 material which closely conforms to the configuration of the rotary cleaning and polishing roll and which are securely retained thereon by means of end plates or heads 34, which are secured by screws or 65 other suitable fastening devices to the ends

of the polishing roll. A plurality of flexible covering is employed to provide a soft yielding surface and in practice the outer one is designed to be replaced as it becomes worn. The vertically disposed thumb nail 70 polishing roll is constructed substantially the same as the horizontal finger nail polishing roll and it is provided with an annular groove 35 and is covered with chamois 36 or other suitable flexible material which 75 is secured on the vertical thumb nail polishing roll by means of upper and lower plates or heads 37.

When the motor is started rotary motion is communicated to the horizontal and vertically disposed nail cleaning and polishing rolls which are arranged to clean and polish simultaneously the nails of both hands. The thumb nail polishing roll is located above the plane of the horizontal finger nail 80 polishing rolls and is in position to operate on the nails of both thumbs when the nails of the fingers are placed above and in contact with the horizontal polishing rolls 24. The front side walls 4 are cut away at 85 90 to afford convenient access to the horizontal nail polishing rolls which are arranged in spaced relation with the front side walls 4 and in parallelism with the same.

In practice, a polishing cream is first 95 applied to the nails after the same have been trimmed and filed and after being operated on by the rotary polishing roll the nails are cleaned and polished by suitable cleaning and polishing material which is applied to 100 the polishing rolls by means of blocks 39 and 40. A series of the blocks 39 is arranged at each of the horizontal nail polishing rolls 24 and a single block 40 is located at the outer side of the vertical polishing 105 roll. The blocks are constructed of suitable material preferably what is known as nail block but any suitable cleaning and polishing material may of course be employed. The series of blocks 39 which are 110 located at each of the horizontal polishing rolls 24 is located in the space between the roll and the adjacent front side 4 of the casing and the said blocks are mounted on approximately vertical arms 41 extending 115 upwardly from a horizontally disposed rock shaft 42 journaled in suitable bearings and connected with operating mechanism which is adapted to swing the arms inwardly and outwardly to carry the polishing material 120 to and from the rotary roll 24. Each block is provided with a backing 43 of fabric or other suitable material having a loop 44 through which the arm to which the block is connected extends. The rock shafts 42 are 125 provided at their adjacent ends with inwardly projecting operating arms 45 normally arranged at an inclination and connected by cords 46 or other suitable flexible connections with a shaft 47. The cords 46 130

extend through suitable guides 48 and 49 and the shaft 47 is adapted to be rotated to swing the inclined arms 45 downwardly to carry the vertically disposed arms inwardly. The 5 block 40 which is located at the outer side of the vertical polishing roll is arranged in a suitable casing or housing 50 and it is connected with a vertically disposed arm 51 pivoted at its lower end and 10 connected with an inclined operating arm 52 and the latter is connected with one end of a flexible connection 53 extending through the guides 48 and 49 and having its other end connected to the shaft 47. The 15 shaft 47 may have the flexible connections 46 and 53 secured to it in any desired manner and it is adapted to be rotated to wind simultaneously the inner portions of the 20 said flexible connections. The blocks of nail cleaning and polishing material are normally maintained out of engagement with the polishing rolls by elastic cords 54 and 55 secured to the casing and extending to the inclined arms 45 and 52 and adapted 25 to lift the same as the flexible connections 46 and 53 are unwound from the shaft 47. Springs or any other suitable means may of course be employed for the yieldable connections 54 and 55. The blocks of the side 30 sets or series are spaced apart and guided to the horizontally disposed polishing rolls by means of guides or flanges 56 arranged vertically and depending from the lower face of removable sections 57 consisting of 35 blocks or pieces of wood covering the spaces between the horizontal polishing rolls and the front side walls 4. The guide flanges 56 which are parallel are arranged at regular intervals and they may be constructed of 40 a single piece of sheet metal bent to form the flanges and top attaching portion 58. The side blocks 39 are supported upon ledges or shelves 58 provided with slots 59 receiving the vertically disposed upwardly 45 extending arms 41 and adapted to permit the latter to move inwardly sufficiently to use practically all of the cleaning and polishing material of the blocks 39.

The device is provided with a lubricator 50 consisting of an oil cup 60, a main tube 61 extending from and communicating with the oil cup and provided with branches 62 connecting the various bearings with the main supply pipe or tube 61. The bearings 55 are located below the level of the liquid within the oil cup so that there will be a gravity feed of the lubricant to the bearings and in practice cotton waste or other suitable material will be arranged in both the oil cups and the bearings to assist in excluding dust and dirt. The bottom of the box or casing is provided at the front below the polishing rollers with openings 63 for the escape of dust and dirt to prevent the powder resulting from the consumption of the

polishing and cleaning blocks from accumulating within the box or casing. The hinged lid or cover 8 is provided with depending extensions 64 which fill the recesses 38 when the lid or cover is closed so as to 70 completely close the box or casing.

What is claimed is:—

1. A nail polishing machine including a pair of angularly related horizontally disposed rotary nail polishing elements arranged to operate simultaneously on the finger nails of both hands simultaneously and a superimposed vertically disposed rotary polishing element arranged to operate on the thumb nails simultaneously 75 with the said polishing elements.

2. A nail polishing machine including horizontally disposed polishing rolls arranged at an angle to each other, a vertically disposed thumb nail polishing roll located 85 above the plane of the said polishing rolls, means for supporting blocks of polishing material adjacent to the said rolls, rock shafts located at the angularly related polishing rolls and provided with arms arranged to move the adjacent blocks of 90 polishing material to and from the said rolls, a centrally arranged arm connected with the block which is located adjacent to the thumb nail polishing roll, a shaft, connections between the shaft and the rock shafts and the arm at the thumb nail polishing roll for moving the said blocks into engagement with the rolls and yieldable means for normally maintaining the blocks out of 95 engagement with the said rolls.

3. A finger nail polishing machine including a rotary polishing element provided with a plurality of nail receiving grooves, a support located upon the polishing element 105 and about which the fingers of the hand are to be bent to position the nails within the grooves in the polishing element, means for rotating the polishing element, and means for supporting blocks of polishing material 110 adjacent to the grooves and below the support and moving the said polishing material into and out of contact with the said polishing element.

4. A finger nail polishing machine including a rotary polishing element, a finger support located adjacent the polishing element, means disposed below the support for supporting a block of polishing material, spaced flanges depending from the under side of the 120 support and adapted to receive the block of polishing material therebetween, means for operating the rotary polishing element, and means for moving the block of polishing material into and out of contact with the 125 rotary polishing element.

5. A finger nail polishing machine including a polishing element, a finger support located adjacent the polishing element, a shelf disposed below the finger support and 130

having a slot therein, the said shelf being adapted to support a block of polishing material, and operating means extending through the slot in the shelf for moving the block of polishing material into and out of contact with the finger polishing element.

6. A finger nail polishing machine comprising a finger nail polishing element, a shelf located adjacent the polishing element and adapted to slidably support blocks of polishing material and provided with slots, arms extending through the slots for moving the blocks of polishing material, and means for operating the arms.

15 7. A finger nail polishing machine comprising a casing, bearings located within the casing, a horizontally disposed shaft journaled in the bearings, a rotary polishing element carried by the horizontally disposed shaft for rotation therewith, a vertical shaft mounted within the casing, a thumb nail polishing element rotatably mounted on the vertical shaft, means for rotating the horizontal shaft so as to effect rotation of the finger nail polishing element, and means for

operatively connecting the horizontally disposed shaft with the thumb nail polishing element so as to cause rotation of the polishing element when the horizontal shaft is rotated.

8. A finger nail polishing machine including a rotary polishing element, a shelf located adjacent to the said element and provided with slots, said shelf being adapted to slidably support a plurality of blocks of polishing material, means for moving the blocks of polishing material into and out of contact with the polishing element and extending through the slots, a removable section overlying the shelf and having spaced depending flanges formed thereon and arranged to extend between the blocks of polishing material so as to guide the same in their inward and outward movements.

In testimony whereof I affix my signature in presence of two witnesses.

ANTHONY V. HOLEC.
